Patented Aug. 20, 1963

196,043

COMBINED STEP AND STOOL

Norvin J. Wehner, Kansas City, Mo., assignor to Cramer Posture Chair Company, Inc., Kansas City, Kans., a corporation of Missouri

Filed Jan. 23, 1963, Ser. No. 73,287

Term of patent 14 years

(Cl. D15—8)

Fig. 1

Fig. 2

Fig. 3

FIG. 1 is a top view of a combined step and stool design embodying this invention. Lines on the top surface are to indicate ribs.

FIG. 2 is a side elevation thereof.

FIG. 3 is a perspective view thereof.

I claim:

The ornamental design for a combined step and stool, as shown and described.
